SIMULATED DRAFT POT-TYPE OIL BURNER

Clarence A. Miller and John Thomson, Petaluma, Calif., assignors to Kresky Mfg. Co., Inc., Petaluma, Calif., a corporation of California

Application May 6, 1947, Serial No. 746,244

4 Claims. (Cl. 158—91)

1

This invention relates to oil burners, and especially to improvements in oil burners of the stimulated or natural draught pot type of the character disclosed in Kresky Patent No. 1,912,713, dated June 6, 1933, Miller Patent No. 2,391,585, dated December 25, 1945, and Miller et al., copending application for patent Serial No. 733,292, filed March 8, 1947. The assignee of the present application and the assignee of the copending Serial Number 733,292 are the same.

It is the principal object of the present invention to provide an oil burner of the stimulated or natural draught pot type wherein air is introduced to the volatile gases for combustion in steps, namely, as primary air, secondary air and auxiliary air. We have found that air introduced in the primary stage, i. e. adjacent to the surface of the oil to be burned, in a more or less restricted area, followed by introduction of secondary air in a greater area and upwardly in the direction of flame outlet, increases combustion efficiency, as disclosed in copending application Serial No. 733,292. The addition of air, which will be referred to hereinafter as auxiliary air, from a point adjacent to the top of the burner and from a point laterally of the path of the flame in the direction of the vertical path of the flame emitted from the burner into the furnace unit and tends to project free carbon or carbon in suspension which has not yet been oxidized into the path of travel of the flame to insure burning thereof in order to produce a more perfect oxidation of the combustible.

We have found that the provision of concavo-convex side walls in an elongated burner of the character generally disclosed in said United States Letters Patent No. 1,912,713, which is provided with spaced apertures for admission of the air, enables us to obtain combustion efficiency of a high order.

Other objects and advantages will become apparent upon referring to the accompanying specification and drawings, in which similar characters of reference represent corresponding parts in the several views.

Referring to the drawings:

Fig. 1 is a top plan view of the burner.

Fig. 2 is a longitudinal sectional view taken on line 2—2 of Fig. 1.

Fig. 3 is a sectional view taken on line 3—3 of Fig. 1.

Fig. 4 is a diagrammatic figure of the burner structure indicating flow of primary, secondary and auxiliary air flow relative to the flame.

The present invention comprises an elongated

2

hollow top casting A, open at the top, as at B, to form a throat for flame emission. The top casting A is provided with vertically depending end walls 2 and depending opposed concavo-convex side walls 3, which said walls 2 and 3 are disposed partially within a bottom casting C.

The top and bottom castings A and C are disposed within an air box D, which in turn is connected to a source of air by a pipe E or the like.

- 10 The bottom casting is provided with end shelves 5, upon which rest the bottoms of end walls 2 of the top casting and with an oil sump 6 disposed centrally of the floor 7, which is inclined slightly downwardly from opposite ends toward the sump. 15 A pipe F is connected to a suitable source of oil supply and leads to the sump 6. The bottom casting is provided with vertical end walls 8 and, preferably, arcuate side walls 9 provided with flanges 11. The side and end walls of the top casting are also provided with flanges 12 and the said flanges 11 and 12 are connected together by bolts 13, or other suitable means. Referring to Fig. 3, it will be noted that the side walls 3 of the top casting are spaced inwardly from the side walls 9 of the bottom casting to form air distribution chambers G. The bottom casting C is spaced inwardly from the air box D so that air entering through pipe E may have access to the air distributing chambers G for emission therefrom. 20 25 30 35 40

through the spaced perforations 14 provided in the walls 3 of the top casting for mixing with the volatile gases in mixing chamber M.

We prefer to provide a plurality of spaced notches 15 in the bottoms of the walls 3, disposed 35 normally adjacent to the level of the oil contained in the said bottom casting. As hereinbefore mentioned, the floor of the bottom casting slopes slightly from opposite ends toward the sump so that oil, admitted into the sump, spreads 40 gradually therefrom over the entire floor of said casting in order to facilitate ignition and quick heating response.

As indicated in diagrammatic Fig. 4, air is introduced into the air box and flows therefrom 45 to distributing chamber G for emission therefrom in the direction of the indicating arrows H, J and K to constitute, respectively, primary, secondary and auxiliary air. The arrows H, J and K indicate the position of primary, secondary and auxiliary air flow in a more or less arbitrary manner as it is obviously impossible to determine precisely where the primary, secondary and auxiliary air flows are defined relative to one another. The auxiliary air K is designated as that air which flows from adjacent to the top of the top casting

into the flame, indicated at L, for the purpose of forcing combustible particles, namely, free carbon, back into the path of the flame for complete combustion thereof. The substantially vertically directed wall of auxiliary air K forces free carbon into the flame L for complete combustion in the furnace unit (not shown) disposed above the throat B of the top casting. Formerly, free carbon which escaped from the mixing chamber was a waste product.

The walls 3, as hereinbefore mentioned, extend the length of the top casting A and protrude convexly toward one another so that at the top of the burner portion, i. e., adjacent to the apertures which admit auxiliary air, the said walls are spaced from one another substantially a greater distance than at the bottom of the burner, i. e., adjacent to the normal level of oil. The distributing chambers G, formed by the concave sides of walls 3 and the inner arcuate surfaces of walls 9 tend to prevent undesirable turbulence and eddying of air emitted therefrom into the mixing chamber M. This is a highly desirable characteristic.

The apertures 14, through which air is emitted, are preferably drilled through the walls 3 in a fashion that air emitted therethrough will flow in the angular direction of the disposition of the wall at that particular point of curvature. Thus air, passing through slots 15 and the holes positioned immediately thereabove, flows fairly parallel to the surface of oil contained in the bottom casting while air emitted from holes higher in the walls is projected upwardly at a progressively greater angle; the auxiliary air being projected upwardly at the steepest pitch.

While we have described our invention in more or less specific detail for purposes of clarity of description by way of example and illustration, it is understood that various changes and modifications may be made within the spirit of the invention and the scope of the appended claims.

We claim:

1. In an oil burner, the combination comprising an elongated bottom member having side walls, a floor portion and a sump portion; said floor portion inclined downwardly slightly from opposite ends toward said sump portion, means to supply oil to said sump portion, a top member having convexly formed side walls convexly opposed to one another disposed partially within said bottom member, said convex walls being of substantially uniform convex curvature extending from a vertical portion at the bottom of the walls to a horizontal portion at the tops thereof, and a plurality of rows of spaced apertures provided in said convex side walls from end to end and top to bottom, said apertures each formed perpendicular to the plane of the wall through which it is provided at the location thereof whereby each succeeding row of apertures from bottom to top of said walls is arranged to introduce air above and across said floor portion at an ever increasing angle relative to the horizontal.

2. In an oil burner, the combination of a bottom member having side walls and end walls, a top member having opposed concavo-convex side walls convexly opposed to one another disposed partially within said bottom member, said concavo-convex walls being each of substantially uniform and equal convex curvature extending from a vertical portion at the bottoms of said walls to a horizontal portion at the tops thereof, and a plurality of rows of spaced apertures provided in each of said concavo-convex walls and arranged from top to bottom and end to end thereof, said apertures each formed perpendicular to the plane of the wall through which it is provided at the location thereof whereby each succeeding row of apertures from bottom to top of said walls is arranged to introduce air above and across said bottom member at an ever increasing angle relative to the horizontal.

3. In an oil burner, the combination according to claim 2 and wherein the bottoms of said side walls of said bottom member are curved inwardly toward one another and said concavo-convex walls of said top member are spaced inwardly from said side walls of said bottom member.

4. An oil burner comprising an elongated mixing chamber open at the top and defined by two convex side walls convexly opposed to one another whereby said side walls are at least twice as far apart at the tops thereof as at the bottoms thereof, each said wall having a substantially uniform convex curvature extending from a vertical portion at the bottoms thereof to a horizontal portion at the tops thereof, and a plurality of rows of spaced apertures provided in said side walls and arranged from top to bottom thereof whereby primary air may be introduced through said perforations adjacent to the bottoms of said walls and auxiliary air may be emitted from said perforations adjacent to the tops of said walls, said apertures each formed perpendicular to the plane of the wall through which it is provided at the location thereof whereby each succeeding row of apertures from bottom to top of said walls is arranged to introduce air into said mixing chamber at an ever increasing angle relative to the horizontal from the bottom toward the top of each said side walls.
